MULTISHUTTLE SHUTTLE CHANGER
LOOM

Richard G. Turner, Worcester, Mass., assignor
to Crompton & Knowles Loom Works, Worcester, Mass., a corporation of Massachusetts

Original application September 27, 1935, Serial
No. 42,375. Divided and this application July
2, 1936, Serial No. 88,649

8 Claims. (Cl. 139—232)

This application is a division of my prior application Serial No. 42,375, filed September 27, 1935, which application relates to multi-color shuttle changer looms, it being the general object of the invention to provide a loom which is preferably continuously running and capable of replacing any one of several weaving shuttles upon exhaustion of weft. This divisional application relates particularly to the shuttle changing mechanism shown but not claimed in said original application.

So far as I am aware shuttle changing looms which have been used commercially have been limited to two-color work so far as the shuttle changing features are concerned. Certain patterns call for a greater variety of color than can be obtained with two shuttles and it is an important object of my present invention to provide a loom which will automatically exchange a depleted shuttle for a fresh shuttle with reserve weft, the loom to operate with more than two shuttles, four being shown in the drawings attached hereto.

In a continuously running loom it is essential that the time intervals allowed for the various operations be sufficiently long to render them commercially dependable and in providing a loom wherein the intervals are of proper length I find it desirable to secure the indication of weft exhaustion and operate the color control comparatively early in the shuttle changing operation. It is a further object of my present invention to provide a pattern mechanism wherein the indication for the shuttle changing mechanism will be at least one pick earlier than the indication for the ordinary box lifting mechanism.

It is a further object of my present invention to provide the reserve shuttle receiving mechanism with a box constructed somewhat differently from those heretofore employed in that it includes in its construction a rear wall which assists in properly placing a shuttle which is moving from the magazine toward active position. As a continuation of this idea it is a further feature of my invention to provide a box cover which shall have a shuttle grasping wall or lip to engage a rear surface of the shuttle and positively move the latter forwardly as the lay leaves shuttle changing position.

It is another object of my present invention to provide an improved form of reserve shuttle releasing mechanism which shall include in its construction an element capable of having two different motions, one of which is normal and the other of which occurs on shuttle releasing beats

of the loom and is dependent for its operation on interruption of the first movement.

A still further object of my present invention is to provide an improved indication storing mechanism under the joint control of the weft detector and the color selector to cooperate with a shuttle releasing mechanism and capable of retaining the setting which will call for replacement of an exhausted shuttle which has passed out of action immediately after giving indication of weft exhaustion.

A further object of the invention relates to improved means for advancing a reserve shuttle from the magazine to the shuttle changing box structure.

When the loom operates with a Knowles head motion to control the boxes and harness the setting of the color selection chain a whole pick ahead of the box chain would result in movement of the selector mechanism during the detecting interval, thereby preventing correct cooperative relation between the active shuttle being detected and the selector. It is a further object of my invention to effect a delay in the selector movement until time has been given the detector to indicate exhaustion. The specific means for accomplishing this result shown herein includes a selector gear cylinder set late with respect to the box gear cylinder, the late setting permitting cooperative relation between the selector and active shuttle during detection, but causing selector movement immediately after detection.

With these and other objects in view which will appear as the description proceeds, my invention resides in the combination and arrangement of parts hereinafter described.

In the accompanying drawings, wherein a convenient embodiment of my invention is set forth,

Fig. 1 is an end elevation of a loom having my invention applied thereto,

Fig. 2 is an enlarged detailed view of the indication storing and reserve shuttle releasing mechanism shown at the bottom of Fig. 1,

Fig. 3 is a plan view of the structure shown in Fig. 2,

Fig. 4 is a detailed vertical section on line 4—4 of Fig. 3,

Fig. 5 is a fragmentary view showing the lower end of the magazine shown in Fig. 1, but on an enlarged scale, illustrating the shuttle release mechanism,

Fig. 16 is a side elevation of the driving gear for the head motion,

Fig. 17 is a detached perspective diagrammatic view of the box and color cylinder gears,

Fig. 18 is a diagram showing the time relations of the several parts of the invention, and

Fig. 19 is a detail plan view in the direction of arrow 19, Fig. 7.

In the following description I will set forth acceptable forms of the color selecting mechanism in Figs. 10 to 13, the weft detecting mechanism at the top left part of Fig. 1, the indication storing mechanism under the joint control of the color selector and weft detector in Figs. 2, 3 and 4, the reserve shuttle selector controlled by the color selector in Figs. 5, 6 and 14, the reserve shuttle release mechanism and magazine in Figs. 1, 5, 6 and 9, the reserve shuttle advancing mechanism in Figs. 1, 7 and 8, and the shifting boxes adjacent the magazine, shown in Fig. 1, which constitute the reserve shuttle receiving structure.

In general, it may be stated that the type of loom to which I have applied my invention employs shifting shuttle boxes, four in the present instance, at the left end of a loom, while the shuttle changing mechanism and the weft detector are both located at the opposite or right hand end of the loom, see Fig. 14. As the lay reaches approximately its midposition when moving forwardly, or at bottom center, with the active shuttle at the drop box end, the box motion will start the shifting of the drop boxes, and shifting is completed when the lay has reached approximately its midposition on the rearward stroke thereof in time for picking, or at top center. Approximately one-quarter of a pick later when the lay is in back center position the reserve shuttle will be placed in a temporarily raised shuttle box under the magazine, while the active depleted shuttle will approach a lower box which has been raised into alignment with the shuttle race for the purpose, boxing occurring approximately at bottom center or shortly thereafter. There will then occur a downward shift of the temporarily raised pair of shuttle boxes so that at the time of picking, half a beat after the shift starts, the lay will be on top center with the fresh reserve shuttle in picking position, the exhausted shuttle having been expelled from its box when the lay started its backward movement after reaching

front center and prior to picking of the fresh shuttle.

Referring particularly to Fig. 1, the loom frame F supports a rocker shaft R about which the lay L swings. The lay has a lay end 1 provided with a plate 2 slotted at 3 to receive a sliding picker not shown. The lay moves back and forth in the loom by connectors 4 operated by the top shaft 5, being shown in front center position in Fig. 1. Shaft 5 is geared in the usual manner to the bottom shaft 6 in a 2 to 1 ratio, the top shaft making a revolution for each beat of the loom, while the bottom shaft rotates once in two beats. The frame supports a magazine M which in turn carries a weft detector W and there are also provided supports for the various mechanisms hereinbefore enumerated for co-ordinating the movements of the magazine to the end that a reserve shuttle may be supplied to correspond with the depleted shuttle which is about to be picked from the drop box end of the loom toward the magazine.

As shown in Fig. 14 I provide a gang of boxes G having four cells I, II, III and IV any one of which may be aligned with a shuttle race 7 of the lay for as many pairs of picks as desired. While there are two shuttle boxes at the right hand end of the loom, as will be set forth more in detail hereinafter, yet only one of these boxes is normally active.

Head motion

Referring to Fig. 16, the loom frame F supports an upright shaft 8 carrying at its bottom a bevel gear 9 meshing with a similar gear 10 on a stub shaft 11 suitably supported. An eccentric gear 12 on the stub shaft meshes with a second eccentric gear 13 on the top shaft, and since the crank shaft turns at a constant rate, the stub and upright shafts will turn with variable speeds.

The upright shaft has top and bottom bevel gears 14 and 15, respectively, meshing with similar gears rotating with top and bottom cylinder gears H and K, respectively, and hence the latter share the variable rate of rotation of the upright shaft. Each cylinder gear has a box milled gear section 16 and a similar color section 17, the box section having teeth 18 and a blank area 19, while the color section has teeth 20 and a blank area 21. The blank area of the color section has a zone 22 extending a space equal in this instance to six teeth beyond the corresponding area of the box section, having respect to the direction of rotation, so that the color section is later in coming to operative position than the box section by a time corresponding to six teeth, see Fig. 17. Each cylinder gear, with its box and color sections, rotates once for each beat of the loom, although this is not a necessary relation.

The head frame 25 supports a heel pin 26 on which are pivoted two box vibrator levers 27 and 28, respectively, and each vibrator lever carries a vibrator gear 29 attached to a connector 30. The connectors operate box lifting levers 31 and 32 operatively connected to vibrators 27 and 28, respectively, and lever 31 carries a sheave 33 for chain 34 connected to lever 32. Levers 31 and 32 are pivoted at 35 and 36, respectively, and operate in well known manner to give the boxes G four different positions by the chain 34 which is attached to them. The box vibrators are operated as usual and can place any one of the shuttle boxes in picking position.

The eccentric gears are set so that the cylinder sections are moving at their slowest rate when the lay is on bottom center and fastest at top center, and furthermore, the box tooth section 18 is in position to start moving the boxes at approximately bottom center, that is, slow time for this particular setting of the head. By this relation a relatively large amount of lay motion is possible with a small angular motion of the color section, and this timing, coupled with the color pattern chain to be described, insures correct cooperative relation between the exhaustion indicating shuttle and the magazine control parts while at the same time affording a relatively long interval in which actual exchange of shuttles can be effected.

Color selector

If shifting of the color selector and indication storing controllers were synchronous with box shifting, the indication would be too late, since it would not be completed until picking from the box end, or only one-quarter of a pick before the back center position where the reserve shuttle should be ready to drop into the temporarily raised box. The selection must therefore come earlier, but if the time be set ahead one whole pick, the indication storing mechanism would be shifting at front center when the feeler detects, with resultant confusion of colors in the shuttle change. It is necessary therefore to delay shifting of the indication storing mechanism until after the feeler has had a chance to indicate exhaustion and set a storing indicator corresponding to the shuttle giving the indication.

The color selector and storing mechanism must remain in cooperative relation with the active shuttle being detected until the feeler has had a chance to effect indication of exhaustion, after which movements preparatory to release of a reserve shuttle can take place, such movements involving possibly a changed setting of parts due to anticipated return to action of a shuttle which indicated exhaustion just before becoming inactive.

The desired timing may be obtained by building the chain so that the selector rolls are one pick ahead of the corresponding box controlling rolls, and then delay effective engagement of the selector cylinder gear with the selector vibrator gear until the feeler has had time to indicate. The vibrator gear must have a certain motion to unlock the connector during which there will be no appreciable motion of the color control parts, and furthermore, the eccentrics may be set so that the slowest part of the vibrator gear motion comes before the detector operates. These various delays added together give the time required to allow the feeler to set a storing indicator before the color selector has had any considerable motion. I wish it to be understood, however, that I am not limited to the particular timing due to the setting of the eccentrics shown, since I have demonstrated that the slow time for the head may occur when the lay is in other positions than that specified. The color selector on the head motion will now be described in connection with Figs. 10, 11 and 12.

Two other vibrator levers 45 and 46 for the color indication are operatively connected by means of vibrator gears 37 and connectors 38 to levers 47 and 48, respectively, moving about pivot 36. Each of the levers 47 and 48 is capable of 75 moving to either of two extreme positions, as in-

dicated in Fig. 12, depending upon the direction of rotation of the associated vibrator gears.

A color selector control lever 50 is pivoted at 51 to the head frame and has a depending arm 52 which is pivoted to a floating lever 53 at 54. The upper end of lever 53 is attached by top link 55 to selector lever 47 at 56, while a bottom link 57 connects the lower end of the lever to the other color selector lever 48 at 58. An upper arm 59 of the lever 50 is attached to a depending connector 60 which extends downwardly under sheave 61 as shown in Fig. 14, across the loom, upwardly to the right of sheave 62, and over to the right of a third sheave 63. The connector is attached as at 64 to the upper arm of a bell crank lever 65 pivoted to the magazine frame and having a horizontal arm 66, see Fig. 6. A tension spring 67 having one end attached to a supporting bracket 68 rigid with the loom frame is attached to arm 64 and normally exerts a pull on the connector 60. The latter is therefore constrained to move to the left of Fig. 6 by forces derived from levers 47 and 48, and to the right by the spring 67 when permitted to have such motion by the positions of said levers 47 and 48. Spring 67 also moves a color slide to be described by a force transmitted through lever 65.

In Fig. 13 I show a continuously running pattern chain P having four spaces for rolls. The chain comprises cross bars 69 connected by links 70 and fed over a chain shaft 71 shown in Fig. 15. The chain is assumed to move in the direction of arrow s in Figs. 10 and 13 and longitudinal rows 72 and 73 are occupied by the rolls 74 and 75 which position vibrators 27 and 28 to control the usual box motion of the loom. The high rolls 74 and low rolls 75 in these two rows 72 and 73 have been set forth to give a varied sequence of motions for the gang of boxes G to produce a desired pattern.

The other auxiliary rows 76 and 77 which I have added comprise high color rolls 78 and low color rolls 79 in the same order as the rolls in rows 72 and 73 except that the rolls on the auxiliary added rows 76 and 77 will have the same sequence as those in rows 72 and 73, respectively, but will be one bar ahead thereof. In other words, the first high color rolls 78 at the right and bottom of Fig. 13 is rows 76 and 77 and located on the second cross bar correspond to the high box rolls 74 in rows 72 and 73 which are to become operative one pick later. By this phase displacement the rolls of the auxiliary rows give their indications to their corresponding vibrator gears 45 and 46 one pick before the corresponding box rolls indicate the box motion.

The high rolls 78 and low rolls 79 on rows 76 and 77 are capable of giving the levers 47 and 48 four different relative positions with corresponding rocking of the color control lever 50 to as many different positions. In Fig. 10 both levers 47 and 48 are thrown to the left and the floating lever 53 is therefore in its left-most position corresponding to the low position for connector 60 with the drop boxes down and cell I active as indicated in Fig. 14. In Fig. 12 lever 48 has been moved to the right while lever 47 remains to the left, these positions being indicated in full lines, from which it will be seen that the pivot 54 has been moved to the next position to the right from the one shown in Fig. 10. Also, in Fig. 12, certain parts are indicated in dotted lines to assume reversed positions for levers 47 and 48, the floating lever 53 thereby being given its next step to the right. In Fig. 11 both levers 47 and 48 have been

- thrown to the right and the center 54 is therefore in its rightmost position with the result that the color control lever is given its extreme counter-clockwise position to move connector 60 to its upper limit. This corresponds to the placing of cell IV in active position. The advance movement of lever 50 effected by the reversal of the position of the levers 47 and 48 indicated in Fig. 12 is due to the fact that the links 55 and 57 are connected to said levers at different distances from the common axis 36. The full line position of Fig. 12 coincides with the activity of box II while the dotted position corresponds to action on the part of box III.
- 15 The indication given by the high and low box rolls on rows 72 and 73 must be completed before the time in the loom cycle for commencement of box shifting. The latter ordinarily starts with the lay at bottom center on the pick which carries 20 the active shuttle into one or another of the cells of the drop boxes, that is, indication from the pattern chain is completed before the shuttle is boxed at the box end of the loom. Inasmuch as the color rolls on the rows 76 and 77 are a pick 25 ahead of the box rolls they complete their indication when the active shuttle is boxed on the plain or magazine end of the loom opposite the drop boxes. The color vibrators and gears are therefore placed when the lay is moving forwardly and 30 the active shuttle is boxed under the magazine. The previous indication corresponding to the active shuttle must be retained, however, until the detector can operate, and this short delay is effected by the location of tooth section 20.
- 35 The box cylinder picks up the box vibrator gears at a bottom center, or at protection, and this would be the time the color cylinder would engage the color vibrator gears, but as previously explained, this would interfere with the weft detector. By having the zone 22 of sufficient length it will be passing by the color vibrator gears while the lay moves the active shuttle forwardly to the detector, and the tooth section 20 will not engage the color vibrator gears until after the detector to 40 be described has had an opportunity to indicate weft exhaustion. This engagement will begin with the lay at or near front center, and will continue during approximately half a beat, so that the lever 50 will be given its full throw by 45 the time the lay reaches back center with the active shuttle travelling toward the drop boxes. At this time, therefore, the arm 66 will have had time to assume a new position and give rod 81 a new vertical setting. Rod 81 rises when the boxes 50 are to have an up shift and descends when the boxes are to drop.

Weft detector mechanism

The weft detector mechanism W is mounted on 55 the magazine and therefore is in a position to detect the active shuttle when the latter is on the magazine side of the loom. A forwardly extending arm 85 secured to the magazine frame has pivoted thereto a lever 86 as at 87, the lever 60 being held against an adjustable stop screw 88 by a tension spring 89. The lower end of lever 86 carries a two-prong electric detector 90 from which lead two wires 91 and 92. The shuttles are provided with bobbins having metallic ferrules normally covered by weft, but upon approach 65 of weft exhaustion the ferrules are uncovered to permit electric connection between the prongs 93, whereupon wires 91 and 92 are electrically connected.

70 75 A changing box lifting lever 94 carries an up-

standing horn 95 on which is mounted a solenoid 96, one side of which is connected to wire 92 and the other side of which is connected by a wire 97 to a source of electric power E which is also connected to wire 91. It is apparent that upon exhaustion of weft in a shuttle S, solenoid 96 will be energized with the lay in front center position. Energization of the solenoid will lift armature 98 pivoted to a trip 99. The latter is pivoted to move around rod 100 supported as indicated in Fig. 3 on the lever 94.

It will be seen with reference to the description given in connection with the color selecting mechanism that the detector indicates exhaustion of weft with the lay on its front center position before the color selecting mechanism has moved appreciably, after which the selector moves. It will be seen that this result is accomplished by a single feeler mounted to permit selective shuttle change as distinguished from previous constructions wherein the detector mechanism was unable to detect the active shuttle. The weft detector shown herein may if desired be substantially the same as shown in my co-pending application Serial No. 667,464 where the detector is claimed.

Indication storing mechanism

Lever 94 carries a second rod 101 parallel to rod 100 and together these rods afford support for a sliding yoke 102 pivotally connected to a positioning rod 103, see Figs. 2, 3 and 4. The latter is connected to a bell crank lever 104 pivoted as at 105 to a stand 106 fixed to a stationary stud 107 which serves also as a pivot for lever 94. As shown in Fig. 1 the lever 104 is connected to the lower end of rod 81 and it is by the connection just described that the yoke slides along rods 100 and 101 in response to changing positions of rod 81 induced by the altering positions of the parts shown in Fig. 10. In other words, the yoke has 30 positions corresponding to those of the cells of the drop boxes illustrated in Fig. 14.

The yoke carries a pivot rod 108 on which are mounted four indication storing elements 109, 110, 111 and 112. These elements are similar 35 and each includes a depending finger 113 for engagement with a dog 114, and each element further has a head at 117. One end of each latch as indicated at 118 is capable of moving into vertical alignment with the bent end 119 of the 40 trip 99, while the other end of the latch is formed with an abutting surface 120 to engage a stop rod 121 carried by the sliding yoke. A spring plunger 122 is operative to hold each indication 45 storing element yieldingly in the position shown 50 in full lines in Fig. 4, a stop bar 123 limiting movement of the heads.

The yoke slides with respect to the trip so that with the movements of the pattern chain one or another of the elements 109, 110, 111 or 112 becomes operatively relatable to the trip, and upon energization of the solenoid as already described the trip will be raised to engage the end 118 vertically aligned therewith and corresponding to the weaving shuttle which happens to be at the 55 magazine side of the loom and depleted.

Energization of the solenoid will rock the selected member 116 about its pivot to unseat the corresponding surface 120 from the stop rod 121, thereby unlocking the associated element, and 60 further upward movement of the trip moves the selector element from the full to the dotted line position shown in Fig. 4 against the yielding action of the spring plunger 122, where the latter will hold the tripped setting element as long 65

as needed. If the indicating shuttle should move out of action upon its return to the drop boxes, the indication storing element will remain set but will be shifted laterally with respect to the trip 99. The indication storing mechanism thus far described may be similar to the structure set forth in co-pending application filed by Cederlund and Holmes Serial No. 665,157.

In carrying my invention into effect I have added a stop shoulder 124 to each of the latch members 116, the shoulder being moved by the solenoid to the dotted line position shown in Fig. 4 to be supported by the stop rod 121 for the purpose of cooperating with a stud 125 longitudinally adjustable in a short lever 126 for purposes to be described more in detail hereinafter. Each latch carries a surface concentric with pivot rod 108 to engage stop rod 121 for the purpose of holding the tripped latch in set position as the indicating element associated therewith moves to indicated position shown dotted in Fig. 4. Rod 121 therefore holds the indicated latch against displacement.

The effect of the mechanism described thus far in connection with Figs. 2, 3 and 4 is to store an indication of weft exhaustion which may be given by any depleted weaving shuttle when on the magazine side of the loom and to throw the stop shoulder 124 corresponding to the depleted shuttle into a position where it can interrupt the normal downward movement of stud 125. The shifting of the yoke 102 will carry an indicated shoulder out of alignment with stud 125 if the corresponding shuttle passes out of action upon its arrival at the box end of the loom.

Reserve shuttle releasing mechanism

The bottom shaft 6 has secured thereto a cam plate 130 which has two alternately operative cams 131 and 132, respectively, see Figs. 1, 2, 3 and 9. Inner cam 131 has a long dwell 133 interrupted by a flat section 134 which constitutes rising and falling surfaces. Outer cam 132 is separated from the flat area 134 by a space 135 slightly greater in width than the diameter of a roll 136 carried by a cam lever 137. Cam 132 has a steep rise 138 and a dwell 139 extending part way around the plate 130, as shown in Fig. 2.

Lever 137 rocks around a stud 140 carried by the rear end of box lifting lever 94 and has pivoted thereto as at 141 the previously described lever 126. A compression spring 142 surrounds a headed bolt 127 which fits into a socket 128 and is loosely guided by a lug 129 on lever 137, as shown in Fig. 2, to hold the small lever against an adjustable stop screw 143 on lever 137.

A lifting arm 145 also pivoted as at 140 has an adjustable screw 146 to engage the left end of lever 137 as viewed in Fig. 2, and has pivoted thereto an upwardly extending rod 147 which controls the releasing of shuttles from the magazine to be described hereinafter.

Lever 137 has a lug 150 extending laterally therefrom through the slotted lower end 151 of a second upwardly extending rod 152. The upper end of this last rod extends to the shuttle advancing mechanism to be described.

During normal operation rotation of the bottom shaft 6 will result in roll 136 following cam 131 because of the greater weight of the left end of lever 137, Fig. 2. Stud 125 is normally held in the raised position shown in Fig. 2 by the dwell 133, but at the desired time in the cycle of loom operation the flat surface 134 arrives under the roll and the lever rocks to cause a periodic

normal descending movement of the stud 125. This downward movement imparts no lift to rod 147 or arm 145 and these last named parts will therefore remain ineffective to alter the shuttle releasing mechanism. In like manner the lug 150 moves down in the slotted end 151 of rod 152 without operatively altering the latter. Under normal conditions roll 136 does not engage cam 132.

Should one of the shoulders 124 be in a position to interrupt the normal downward movement of stud 125, however, the steep incline 138 will pick up the roll 136 and depress the latter, thereby raising the left end of lever 137 to elevate rod 152 and cause lifting of arm 145 to raise the rod 147. The inner end of incline 138 is located within the projection of concentric dwell 133 far enough to permit a limited descent of stud 125 to shoulder engaging position without causing too abrupt engagement with roll 136.

The two conditions therefore which result from interruption of normal downward movement on the part of stud 125 are the raising of rods 147 and 152 which control the shuttle releasing mechanism of the magazine and the shuttle advancer, respectively. The upward movements of rods 147 and 152 are preferably limited to cause proper operation of the parts which they move, and should this motion be less than that which would otherwise be imparted to them by lifting of lever 94, the small lever 126 can yield against the motion of spring 142 to relieve said rods of undue strain.

Magazine and shuttle release

The magazine M has inner and outer plates 160 and 161 between which are arranged four stacks A, B, C and D of diverse reserve shuttles. The stacks are arranged in two pairs with a thin partition 162 between the stacks of each pair, and the pairs may be separated by a vertical plate 163 having vertical guide ribs 164 against which lie adjacent surfaces of the shuttles in the inner stacks. The inner vertical edge of plate 163 is spaced from the adjacent part of the magazine to afford a thread passage, as shown at 83, Fig. 6. The thin partitions are also spaced from magazine plate 160 to define thread passages 84. The back of the magazine has a brace 165 with shuttle guiding ribs 166, while a front brace 167 is provided with other vertical guide ribs 168. The parts 162, 163 and 167 are supported from the outer magazine plate 161 as suggested in Fig. 6.

The magazine has four shuttle releasing rocking shafts 169, 170, 171 and 172 corresponding respectively to stacks A, B, C and D. Each shaft has secured thereto a shuttle supporting and releasing finger 173 and a reserve shuttle holding pad 174 of friction material, such as rubber. Normally the supporting fingers are in the position suggested in Fig. 5 so that all of the shuttles in the stacks are supported, but when the shaft of a stack from which a reserve shuttle is to be drawn rocks, the supporting finger moves from under the lowermost shuttle to permit the same to fall on supports 220 and at the same time the supporting pad 174 moves into position to prevent descent of the superposed reserve shuttles. These parts may be similar to the corresponding features of my prior Patent No. 2,054,171, issued Sept. 15, 1936 to which reference may be had for a more complete description of the shuttle releasing and supporting mechanism.

Each rocking shaft has an operating trip finger 175 and said fingers are adapted for depression by one or another of two depressing arms 176 secured to a color slide 177 capable of sliding and rocking. An elongated rib 178 is secured to the slide 177 and is located between a pair of fingers 179 on a rocking lever 180 pivoted about the slide 177. The upper end of lever 180 is connected to a rod 181 the inner end of which is attached to a bell crank lever 182 movable about a fixed axis and operatively connected to the upper end of rod 147. Normally the rod 147 is down as already described but when it is raised during the shuttle changing operation it rocks levers 182 and 180 to cause turning of the slide 177 in such a direction as to depress the arms 176 by a force transmitted through the web 178.

It will therefore be seen that upward movement of rod 147 operates to release a reserve shuttle from the magazine, since downward movement of an arm 176 will depress a finger 175 to rock one or another of the shuttle releasing shafts.

25   *Reserve shuttle selector*

The lever 65 has extending outwardly therefrom a rod 185 attached to the rear end of a bell crank color slide moving lever 186 pivoted as at 187 to a fixed bracket 68, see Figs. 5 and 6. This connection permits rocking and sliding of part 177. The relation of the arms 176 and the fingers 175 is set forth in Fig. 6, from which it will be understood that the spacing of these fingers and arms is such that rocking of the slide 177 can cause depression of but one finger 175 at a time. The connection 60 which is operatively related to lever 65 operates in timed relation with respect to the shifting of the boxes at the opposite end of the loom and therefore the longitudinal position of the color slide 177 is determined by the head motion shown in Fig. 10 and in coordination with but prior to shifting of the gang of boxes G. The color slide rocks in bearings 191 and 192 supported on the outer end of the magazine.

It will be seen that the structure shown in Figs. 5 and 6 operates to select a stack corresponding to the depleted shuttle by mechanism coordinated with the shifting of the drop boxes and effecting longitudinal motion of slide 177, and also that after the selection is made the color slide is rocked by rod 147 to effect delivery of the lowermost shuttle in the magazine stack corresponding to the shuttle which is to be replaced.

55   *Reserve shuttle advancing mechanism*

Pivoted on stud 107 is a lever 200 normally urged against a cam 201 by a compression spring 202 interposed between the lever and the stand 106, see Figs. 1, 7 and 8. Cam 201 is secured to the top shaft of the loom and makes a revolution each loom beat to move the upper end of the lever forwardly, or to the left in Fig. 7, by a force exerted through roll 203. An actuator arm 204 is pivoted as at 205 to the lever and has an elongated arcuate slot 199 the forward end of which communicates with a notch 206 65 extending downwardly and defining a shoulder 207. An actuator arm 208 moves about fixed pivot 209 and carries a pin 210 which extends into the slot 199. A rod 211 is pivoted as at 212 to a part of the arm 208 and extends through 70 a web 213 on one of two connected advancing

arms 214 pivoted about axis 209. A compression spring 215 limited by nuts 216 exerts a yielding force between the arms 208 and 214 tending to move the latter forwardly or to the left in Fig. 7 whenever arm 208 is moved forwardly by 5 shoulder 207.

The arms 214 have an advancing head 217 pivoted thereto from which extends rearwardly a guide rod 218, passing through a fixed guide eye 219. The lay has a pair of the previously 10 mentioned arcuate shuttle receiving supports 220 extending rearwardly therefrom along which the advancer head 217 moves during a shuttle changing operation.

Under normal condition the actuator arm 204 15 is down, being supported by pin 210. A lifting pin 221 on the upper end of rod 152 extends through a guide slot 222 in the advancer arm and into slot 199. Under these conditions the actuator arm moves back and forth each beat 20 of the loom, the slot 199 having an idle motion with respect to the pin 210, with the result that the head 217 is normally at rest. When the rod 152 is raised as already described preparatory to a shuttle changing operation the pin 221 will 25 elevate the actuator arm so that the shoulder 207 will be horizontally aligned with the pin 210, whereupon forward motion of said arm 204 by the cam will rock the actuator arm in a counterclockwise direction about axis 209 as viewed in 30 Fig. 7. There results a tendency to compress spring 215 which is communicated to the advancer arm and the latter, unless obstructed by an improperly positioned shuttle, will move from the full to the dotted line position shown in 35 Fig. 7. Upward motion of rod 152 is timed to occur when cam 201 is in such position that notch 206 is under pin 210.

The advancer head is normally behind the rearmost stack of the magazine so that a shuttle dropping from said stack, as indicated in Fig. 7, will fall in front of the head. The guide rod 218 and eye 219 serve to hold the head in correct position with respect to the fresh reserve shuttle as the latter slides along the supports 45 220. The pin 221 will ordinarily be held up by surface 139 of cam 131 long enough to maintain driving relation between the shoulder 207 and the pin 210 throughout the shuttle advancing operation, but I do not wish to be limited to this 50 arrangement for maintaining operative connection between the shoulder and actuator pin.

The cam 201 accompanies the forward motion of the advancing head by an incline 223, and the cam also has a high dwell 224 which maintains the head and therefore the reserve shuttle 55 in proper position to drop into the shuttle box to be described for a sufficiently long time to insure correct boxing. As the cam 201 continues to turn the spring 202 returns the actuator head 60 to its rear position and the rod 152 is released to fall so that arm 145 can again drop to permit slot 199 to be aligned with the actuator pin 210. It should be noted that when the head which moves the incoming shuttle is in its extreme 65 forward position it is substantially aligned with the front center partition of the magazine as indicated in dotted lines in Fig. 7. While this is desirable, yet I do not consider it an essential relation. Movement of a reserve shuttle from 70 the front stack toward the lay in a manner to be described hereinafter is facilitated by having the head in the dotted line position in Fig. 7 to serve as a guide and continuation of the aforesaid front center partition, but it will be understood 75

that so far as this front cell is concerned the advancing head does not move the shuttle forwardly by an appreciable amount as is the case with the cells behind the front stack.

5 *Reserve shuttle receiving mechanism*

That end of the lay adjacent the magazine will be provided with upper and lower shuttle boxes 230 and 231, respectively, see Figs. 1 and 7, the boxes being normally down so that the upper box is active and opposite a shuttle binder 232 which is substantially fixed with respect to the lay and does not share the rising and falling movements of the boxes. It will be noted with respect to Fig. 7 that the box structure comprises a back wall 233 which is in front of the lay plate 2 and it will further be seen that the forward ends of the supports 220 extend forwardly as at 235 beyond the front surface of the guide plate 2 sufficiently to direct a reserve shuttle downwardly into the top box when the cover 236 for the latter is raised. The cover has a rib 234 extending downwardly to engage the rear wall of a shuttle being inserted into box 230, and this rib aligns with the wall 233. The cover and its rib are notched as at 237, Fig. 19, to permit raising of the cover without interference with the overhang 235.

The cover 236 has a lug 183 to engage a stationary cam 184 carried by the magazine during the rearward motion of the lay on a shuttle changing beat. The box 230 will rise soon enough to effect this engagement and the cam will throw the cover up to the dotted position shown in Fig. 7 in time to receive the incoming shuttle at back center. Furthermore, the box structure has an abutment 193 to engage a detector withdrawing arm 194 pivoted to lever 86 and resting normally against a stop 195 on said lever. When box 230 is descending after receiving a reserve shuttle and the lay is advancing, the abutment will strike arm 194 and rock lever 86 to carry the detector forwardly far enough to clear the moving box and fresh shuttle.

The previously described dog 114 is pivoted to an actuator lever 240 moving about the fixed pin 107 by means of a cam 241. This cam may be formed as indicated in Fig. 1 and operates in substantially the same manner as does corresponding structure shown in my aforesaid application Serial No. 585,564. When one of the indication storing elements directs the dog under the ledge 238 of lever 94, see Fig. 4, the latter will be raised by upward movement of the forward end of actuator 240 with resultant upward movement of a box lifter rod 242 which is operatively connected to the box lifter lever 94 by structure indicated in Fig. 1. When the boxes rise and the lay moves rearwardly the cover 236 will be raised from the full to the dotted line position shown in Fig. 7 by mechanism not set forth herein but shown in aforesaid application Serial No. 460,746, the result of which is to leave the top of box 230 open so that a shuttle which has been moved forwardly by the advancer head will be able to drop into the upper box 230 by gravity, falling along the wall 233. As cam 241 continues to turn the boxes will descend and the incoming shuttle will be brought into engagement with the stationary binder, being caught between the latter and the back wall of the shuttle box. The frictional contact between the box back and the shuttle assists materially in moving the incoming shuttle down as the boxes fall, this motion further being aided by the

cover 236 which moves back to the full line position shown in Fig. 7 as the boxes descend. For a further description of the mechanism for raising the boxes 230 and 231, reference may be had to the last named application.

5

Operation

In normal operation, the pattern chain will have an advance movement each beat of the loom and the boxes will shift according to the desired pattern to render active any one of the weaving shuttles S¹, S², S³ and S⁴. The pattern chain will be built with the bars in pairs since there is no shifting on that beat of the loom when the active shuttle is at the magazine side.

With each shift of the boxes there will be a corresponding motion of lever 50, which occurs, however, before box movement, the indication for the color vibrators being one pick in advance of the indication for the box motion, and the color cylinder section being delayed so that it does not pick up the color vibrator gears until after the weft detector has had an opportunity to operate. The color selector at the magazine and the group of indication-storing elements will therefore remain in register with the active shuttle when the latter is at the magazine end sufficiently long to permit the detector to set the storing element corresponding to the detected shuttle. Immediately thereafter, however, the color selector and storing elements begin to shift.

Fig. 18 shows the time relations of the several parts of the invention, two complete beats of the loom being represented. The top tier represents the position of the active shuttle with reference to the lay positions indicated by the bottom tier #10. In the latter, F. C. stands for front center position of the lay; Top C. for the top center; B'K. C. for back center; and, Bot. C. for bottom center. The vertical lines represent 15 degrees of angular position of the crankshaft, and the shaded areas represent periods of motion of the several mechanisms identified.

At the left F. C., Fig. 18, with the active shuttle boxed at the magazine end, the detector will be detecting, as represented by the shaded area in tier #2. Shortly after this F. C. position the effective movement of the parts represented in tiers #1, #3 and #4 will start and continue until the lay is nearer back center than top center. The area in tier #2 shaded in dotted lines represents entry of the feeler into the shuttle box 230 when the active shuttle is at the drop box end and no detection is possible. The color vibrator position is shown in tier #8 and the period of engagement for the color vibrator gear is shown by the shaded area in tier #9. The difference in length between the shaded area of tier #9 and those of tiers #1, #3 and #4 represents the unlocking of the vibrator connector, as already explained.

The selected reserve shuttle is released as indicated by the shaded area in tier #5 after the selector has come to rest, and thereafter the reserve shuttle advancer comes into action at a time indicated by the solid line shaded area in tier #6, the time interval between these areas permitting the shuttle to cease vibration due to falling. The dotted line area in the latter tier represents the forward motion of head 204 occurring during part of the time the active shuttle is boxed at the magazine end and is moving toward the drop boxes, this motion of head 204 being without effect, since it starts before reserve shuttle release. Head 204 is preferably back in rearmost

75

position before reserve shuttle release, see tiers #5 and #6, to insure placing of the pusher head 217 behind the rearmost stack of reserve shuttles.

Since lever 137 controls head 204 as well as the shuttle release, there is a further reason for delaying shuttle releasing, namely, to permit unobstructed up motion of head 204 if necessary. This is apparent from Fig. 18, where the dwell between shaded areas suggests that the advancer head is back before the reserve shuttle is released. While I have shown a one-pick cam for operating the advancer head 217 yet I do not wish to be limited to this construction.

The reserve shuttle advancer completes its forward motion and places the reserve shuttle in correct vertical position for change before the lay reaches back center when the active shuttle is moving toward the magazine end, and the box 230 is also up by action of cam 241, dog 114 and lever 94 before the same back center, as shown by the shaded areas in tiers #6 and #7. As the lay reaches back center, therefore, the incoming shuttle, being backed by head 217, falls into the raised box 230. Box 230 is represented as up at top center to permit cover lug 183 to engage cam 184 and raise the cover.

Head 217 then recedes, but the boxes 230 and 231 remain raised until the ensuing bottom center, or slightly thereafter, to permit the outer going depleted shuttle to enter box 231. After boxing, the boxes descend to permit the depleted shuttle to be ejected under the stationary binder by lay motion when the lay is at front center, as indicated at the right end of Fig. 18, where the shuttle changing boxes are represented as down, permitting picking of the freshly inserted reserve shuttle.

The timing suggested in Fig. 18 is desirable, but I do not wish to be limited to the exact relations or intervals represented. The various parts already described will be set to give the sequences illustrated.

The control exercised by the indication storing mechanism is such that a shuttle giving indication of exhaustion and on the magazine side can effect setting of its corresponding storing element and then move out of action when next arriving at the drop box end, after which another shuttle may become active and which during its period of activity may be replaced without loss of the indication given by the first shuttle.

From the foregoing it will be seen that I have provided a multicolor shuttle changing loom capable of operation with more than two shuttles and wherein the weft detector is on the magazine side. It will also be seen that the pattern control is so constructed that the shifting of the color selector and indication featuring mechanisms is delayed until the weft detector has had time to operate, thereby insuring registry between the active shuttle being detected and its corresponding indicating element. This result as accomplished by the specific means set forth herein includes a pattern chain having an auxiliary section built like the main section but one pick in advance thereof, together with the modified form of mutilated cylinder for the vibrator gear which will effect the desired delay to be exercised by the color selection. Furthermore, the cam which controls lever 137 is capable of giving said lever two different motions one of which is normal and the other of which is due to interruption of the normal motion by one or another of the indication storing elements. The shuttle advancing head 217 is preferably so con-

structed as to maintain a more or less parallel relationship with respect to the back wall of the reserve shuttle being advanced toward shuttle changing position. Also, the shifting box 230 which receives the incoming shuttle is provided with a rear wall, and its cover is correspondingly formed, so that the shuttle is under better control during the shuttle changing operation than has been the practice heretofore.

The selector mechanism shown in Figs. 2, 3 and 4, and the pattern control shown in Fig. 10, are not claimed herein but are described and claimed in my copending application Ser. No. 42,375, filed September 27, 1935.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a reserve shuttle, a reserve shuttle receiving shuttle box, pivoted reserve shuttle actuating means, a shuttle engaging head pivoted to the means, shuttle support means on the lay under the engaging head, mechanism to move the pivoted actuating means on shuttle changing beats of the loom, a guide rod extending rearwardly from the shuttle engaging head, a reserve shuttle magazine to deposit a reserve shuttle on the support means in the path of the shuttle engaging head, and a guide through which said rod extends, said guide rod and guide effective to preserve substantially the same angular setting of the shuttle engaging head as the latter is moved by the actuating means to move the reserve shuttle toward the shuttle box.

2. In a shuttle changing loom having a lay, a lay end thereon having a vertical wall, shuttle supports extending rearwardly from the wall to receive reserve shuttles and said supports projecting forwardly of and over said wall, a shuttle box moving with the lay and normally down, a rear wall defining part of the shuttle box which lies substantially under that part of the support projecting in front of the first named wall, a reserve shuttle magazine to release a reserve shuttle so that the latter falls onto the supports, and means to raise the shuttle box into proximity to the support, whereby a shuttle moving from the support will pass over the part thereof projecting in front of the wall and be directed downwardly in front of the rear wall of the shuttle box.

3. In a shuttle changing loom having a lay, a lay end thereon, a shuttle support extending rearwardly from the lay end and having an overhang which projects forwardly from the lay end, said support positioned to receive a reserve shuttle, a reserve shuttle receiving shuttle box, a rear wall forming part of the shuttle box normally lying substantially under the overhang of the support, and a reserve shuttle magazine to deposit a reserve shuttle on said support, whereby a shuttle moving along said support and over said overhang will be capable of moving into the shuttle box in front of the rear wall of said box.

4. In a shuttle changing loom having a lay, a reserve shuttle receiving support extending rearwardly from the lay, a normally down reserve shuttle receiving shuttle box, a rear wall forming part of the shuttle box lying under the forward end of the shuttle support, a reserve shuttle magazine to release a reserve shuttle so that the lat-

ter falls onto the supports, and means to raise the shuttle box into proximity to the support with the rear wall of said shuttle box lying substantially behind the forward extremity of the support, whereby a reserve shuttle moving forwardly off the support will be capable of moving downwardly into the shuttle box in front of said rear shuttle box wall.

5. In a shuttle changing loom having a lay, a reserve shuttle magazine to release a reserve shuttle, a shuttle box normally down, a rear wall forming part of the shuttle box, a cover for the shuttle box movable upwardly from normal down position and returnable to normal position, a web formed on the cover in substantial vertical alignment with the rear wall of the shuttle box, and means to guide a released reserve shuttle under the cover when the latter is raised and into the shuttle box into a position in front of the rear wall of the box, said web movable to a position behind the shuttle to engage the latter when the cover returns to normal position and insure movement of the shuttle with the lay.

6. In a shuttle changing loom having a lay, a reserve shuttle magazine to release a reserve shuttle, a movable shuttle box normally down, means to raise the shuttle box, a rear wall for the shuttle box, a cover supported by the lay and moving therewith and pivoted to move upwardly from normal position with respect to the shuttle box when the latter is raised, a depending web on the cover normally in substantial vertical alignment with the rear wall of the shuttle box, and means to guide a reserve shuttle into a shuttle box when the cover and shuttle box are raised and move said reserve shuttle to a position in front of the rear wall of the shuttle box and in front of the normal position of said web, whereby the web will move to a position behind the shuttle

when the cover returns to normal position and insure movement of the shuttle with the lay.

7. In a shuttle changing loom having a lay, a lay end on the lay, a reserve shuttle support extending rearwardly from the lay end and having an overhang projecting forwardly from said lay end, a reserve shuttle magazine to release a reserve shuttle so that the latter falls onto the supports, a shuttle box, a rear wall for the shuttle box normally under the overhang of the support, 10 a cover for the shuttle box, a depending web on the cover normally substantially vertically aligned with the rear wall of the shuttle box and lying under said overhang, means to raise the cover, and means thereafter operative to direct 15 the reserve shuttle from the support over the overhang into the shuttle box in front of the rear wall of the latter, the web effective when the cover returns to normal position to engage the rear wall of the shuttle to insure movement 20 thereof forwardly with the lay.

8. In a shuttle changing loom operating with a weaving shuttle and having a reserve shuttle, a reserve shuttle receiving shuttle box, a movable head to move the reserve shuttle toward the shuttle box, a regularly moving element having a positive working stroke, a normally stationary member to be connected to the regularly moving element, means operative upon exhaustion of weft in the weaving shuttle to connect the member and element before the latter has a working stroke 25 on a shuttle changing beat of the loom, a second normally stationary member connected to the movable head, and a yielding connection between the members to transmit a yielding force 30 from the first to the second member during a working stroke of the element to move the head toward the shuttle box.

RICHARD G. TURNER.
